PAUL CARLTON ELLIOTT, OF LAWRENCE, KANSAS.

CURVING RIB FOR THE SUPPORTING-SURFACES OF AEROPLANES.

1,115,291.

Specification of Letters Patent.

Patented Oct. 27, 1914.

Application filed February 3, 1914. Serial No. 816,137.

To all whom it may concern:

Be it known that I, PAUL C. ELLIOTT, a citizen of the United States, and a resident of Lawrence, in the county of Douglas and State of Kansas, have made certain new and useful Improvements in Curving Ribs for the Supporting-Surfaces of Aeroplanes, of which the following is a specification.

My invention relates to improvements in aeroplanes, and particularly to the supporting ribs of the planes thereof, of that type which may be curved, or the curve eliminated at the will of the operator, my object being to provide ribs of certain structure whereby the supporting beams of the plane may be utilized, to affect the desired curvature of the rib, by rotating the said supporting beams.

In carrying out this and other objects I may utilize several structures, of which the preferred are shown in the accompanying drawing forming a part of this specification, and in which—

Figure 1 is a sectional side elevation, showing a rib of certain structure, together with portions of the supporting beams in section and in operative connection with the rib. Fig. 2 is a plan view of the device shown in Fig. 1, Fig. 3 is a detail vertical section therethrough taken on the line 3—3 of Fig. 2, Fig. 4 is a view similar to Fig. 1, illustrating a modified structure, and Fig. 5 is an enlarged vertical section taken substantially on line 5—5 of Fig. 4.

Referring now to these figures, and particularly to Figs. 1 to 3 inclusive, I provide a rib composed of two strips A and B formed of wood, metal or other suitably flexible material, and connected by a plurality of vertical transverse connections C, spaced apart throughout the length of the strips A and B, and so associated therewith as to compensate for a difference in linear motion between such strips when the rib is curved more or less or the curve entirely eliminated. To this end the several connecting members C are preferably secured to one of the strips and loosely engaged with the other strip. Certain of these connecting members at spaced points, and particularly indicated at C' are substantially enlarged, and provided with squared transverse bores through which are extended the supporting beams D and E, it being seen by reference to Fig. 3, that these connecting members C' are secured to the lower strip B, and loosely en-

gage the upper strip A. This latter arrangement may, however, be reversed if desired. Thus, it will be seen that when the beams D and E are rotated in relatively opposite directions, the effect will be to either increase or decrease the curvature of the rib, and in order to eliminate the necessity of applying such rotative movement to both of the supporting beams, I may provide them with double cranks d and e, the upper end of each of these cranks being connected to the lower end of the other crank by a connecting rod F. Thus, the rods F cross, as shown in Figs. 1 and 2, and effect the desired result. In similar manner, the upper and lower strips G and H of the form shown in Figs. 4 and 5 are each provided with a plurality of rigid clips, these clips being respectively seen at g and h, and being loosely connected by virtue of slots in the clips h through which portions of the clips h pass in order to compensate for the difference in linear motion between strips G and H, as before stated. Certain of the clips h in this form of my invention have squared openings through which the similar shaped supporting beams I and J pass, these supporting beams having upwardly and downwardly projecting cranks respectively, which are connected by a rod K. In this manner I accomplish the desired result so that it is at once simple and effective, and eliminates all possible interference with other parts of an aeroplane in connection with which my improved rib and beam structure is to be utilized.

The particular means I have shown, while capable of considerable variation, are especially desirable in that they may be applied to any machine embodying a supporting or sustaining surface in the nature of a plane, and on ordinary types of machines they may be substituted for those already in use.

The camber can be changed from a straight line to any necessary curve and in a uniform curve, and maintained in such position or curve.

By using these ribs and supporting beams the plane or planes on one side of the machine may be curved without changing the curve of the plane or planes on the opposite side of the machine, which is of especial advantage in maintaining lateral stability. Further advantages are (1st) greatly increased speed may be obtained by decreas-

ing the camber, (2nd) the factor of safety in rising from the ground and alighting is greatly increased, (3d) the machine can be more quickly raised from the ground, and 5 (4th) the carrying capacity of the machine greatly increased. It is also to be understood that the plane or planes on both sides of the machine may be simultaneously curved.

10 I claim:—

1. In a structure of the character described, the combination of a supporting rib and supporting beams, the former of which consists of upper and lower strips and a 15 plurality of connecting members rigidly connected to one of the strips and loosely engaging the other strip and through certain of which connecting members the said supporting beams are fixed, and connections 20 between the supporting beams for causing their rotation in relatively opposite directions.

2. In a structure of the character described, the combination of a flexing rib, 25 and supporting beams fixed at spaced points to the rib and constrained to rotary movement in relatively opposite directions.

3. In a structure of the character described the combination of a supporting 30 rib, consisting of upper and lower flexing strips, and connections between the said strips to permit flexing movement thereof, and supporting beams non-rotatably extended through certain of said connections and

constrained to rotary movement in relatively opposite directions, for the purpose 35 described.

4. In a structure of the character described, the combination of a supporting rib consisting of upper and lower strips, and a 40 plurality of connections between the strips to permit of their flexing movement, certain of said connections having squared apertures, and squared supporting beams extending through the squared apertures of 45 the said connecting members, and constrained to rotary movement in relatively opposite directions.

5. In a structure of the character described, the combination of a supporting 50 rib consisting of upper and lower flexing strips, and a plurality of connections between the strips to permit of their flexing movement, certain of said connections having squared apertures, squared supporting 55 beams extended through the squared apertures and provided with crank arms projecting in relatively opposite directions, and a connecting rod extending between the ends of the crank arms whereby to constrain 60 the supporting beams to rotary movement in relatively opposite directions, all for the purpose described.

PAUL CARLTON ELLIOTT.
